CONTAINER

Arthur P. Klasing, Webster Groves, and Benjamin M. Williams, St. Louis, Mo., assignors to Gaylord Container Corporation, St. Louis, Mo., a corporation of Maryland

Application October 12, 1949, Serial No. 121,022

5 Claims. (Cl. 229—23)

1

This application is a continuation in part of our pending application Serial No. 643,339, filed January 25, 1946, for patent for Container, now abandoned.

This invention relates to a container having side and end walls and a bottom as essential component parts or portions forming the container, and the invention is more particularly directed to a new reinforced wall structure, the reinforcing being preferably at the upper portion of the wall or walls and one or more of which walls may have a handhole therein disposed below the upper marginal edge of the wall and adjacent the new reinforced wall structure. Further, a lower edge portion of the reinforcing structure may be, and preferably is, substantially in alignment with the upper edge of the handhole or handholes. The invention also consists of a new completely preformed, substantially flat blank including component parts or portions thereof which when folded results in the new reinforced wall structure.

This invention further relates, in a more specific sense, to multiple trip fibreboard bottle containers, designed for service life of fifteen or more return trips for reloading. Containers of this class comprise a bottom panel, side walls with hinged half-cover panels along the upper margins thereof and end wall panels with handholes therethrough for lifting and handling the container. Such heavy duty service demands highly rigid and substantial construction throughout, including the end wall panels which are subject to excessive heavy outward endwise deflection, as well as vertical stacking stresses. Containers of this class are usually lifted and carried when loaded with beverages by grasping one end only by the handhole whereby the entire weight is borne by the portion of the end wall panel at and above the handhole.

One object of the invention is to provide a container of the class described with end walls formed from a blank having novel scores or creases therein, shaped and positioned relative to one another and to the handholes therein to form a solid three-ply reinforced structure above the handholes to the upper edge of the end wall panel, when assembled by folding an upper portion of an upper marginal flap of the end blank, inwardly about one score flatwise against a lower section defined by a second score and then folding the two face to face plies thus formed, inwardly about the second score into engagement with an adjacent wall portion thus providing the three-ply reinforced structure with a lower

part of the structure in horizontal alignment with the upper edge of the handholes.

Another object of the invention is to provide a container having side and end walls and a new reinforcing structure for one or more of the said walls and wherein the reinforcing structure is preferably at the upper portion of a wall or walls and one or more of such walls may have a handhole therein, and a lower edge portion of the reinforcing structure may be and preferably is substantially in alignment with the upper edge of the handhole or handholes, and also a new blank from which the said reinforcing structure is formed.

Another object is to provide the end wall panel with a downturned fold of fibreboard terminating in a relative wide plane perpendicular with the end wall panel in accurate alignment with the upper edge of the handhole therein, a plane surface parallel to the end wall panel in flatwise contact therewith, having a solid inwardly projecting rigid rib of about three times the thickness of the fibreboard.

Another object is to provide an end wall panel for containers of the class described with a reinforcement on the inner side thereof, extending from the upper edge of the end panel to the upper edge of the handhole therein, constructed of an extension of the end panel folded about two horizontal scores having grooves and ribs of such width, contour, and relation of median lines and spacing to each other and to the handhole as to form a solid reinforcing rib at the upper edge of the end panel enclosing the free end of the fold of the panel extension in abutting relation thereto, and a solid reinforcing inwardly projecting rib in accurate register with the upper edge of the handhole.

Still another object is to provide the channels or grooves of the scores in the marginal extension of the end wall panel for containers of the class described with upper boundary lines deeper than the lower boundary lines thereof by an amount that will result in invariable bending of the fibreboard sharply and accurately along predetermined horizontal axes to form solid reinforcing rib elements at the upper edge of the end panel and the upper edge of the handhole.

Other objects are to provide tight solid folds which will eliminate roach pockets and facilitate either manual or automatic machine stapling, gluing or otherwise attaching the folds to the end wall.

The invention consists in the container end wall structure and the end wall blank, and in the

construction, combinations and arrangements and parts hereinafter described and claimed.

In the accompanying drawings, which form part of this specification and wherein like symbols refer to like parts wherever they occur,

Fig. 1 is a plan view looking at the inner face of one of the end wall blanks for a container embodying our invention.

Fig. 2 is a view similar to Fig. 1, showing the completely folded end wall blank.

Fig. 3 is a perspective view of the container, with one of the upper corners thereof shown broken away.

Fig. 4 is a vertical cross-sectional view on the line 4-4 in Fig. 3.

Fig. 5 is an enlarged fragmentary vertical cross-sectional view similar to Fig. 4.

Fig. 6 is a vertical cross-sectional view on the line 6-6 in Fig. 5.

Fig. 7 is a fragmentary view similar to Fig. 5 showing the covers raised and their meeting flanges disengaged from the notches in the end walls.

Fig. 8 is a vertical cross-sectional view on the line 8-8 in Fig. 7.

Fig. 9 is a horizontal cross-sectional view on the line 9-9 in Fig. 7.

Fig. 10 is a horizontal cross-sectional view on the line 10-10 in Fig. 7.

Fig. 11 is an enlarged fragmentary sectional view of the blank on the line 11-11 in Fig. 1.

Figs. 12, 13, 14 and 15 are enlarged sectional views similar to Fig. 11, showing the contour of the scored portions along which the upper marginal flap of the end wall is progressively folded upon itself and against the inner face of said end wall.

Fig. 16 is a perspective view of the end wall blank looking at the outer or printed side or face thereof and showing the position and shape of the scored portions and their relation to one another and to the handhole before folding.

Fig. 17 is an enlarged fragmentary sectional view of an end wall blank provided with a conventional score.

Fig. 18 is a view similar to Fig. 17, showing the end wall blank folded along such conventional score or crease in contrast to the corresponding fold shown in Fig. 13 resulting from the use of the specially designed crease; and

Fig. 19 is a view similar to Fig. 17, showing the blank folded in reverse along the same conventional score or crease in contrast to the corresponding fold shown in Fig. 15 resulting from the specially designed crease.

In the accompanying drawings, our invention is shown embodied in a fibreboard container comprising a bottom 1 with upstanding end flanges 2, end walls 3 with horizontally elongated handholes 4 therethrough and side walls 5 with end flanges 6 and hinged covers 7, each cover closing half of the container and having a depending flange 8 along its free side edge and depending end flanges 9. The end flanges 2 of the bottom 1 and the end flanges 6 of the side walls 5 overlap and are rigidly secured by staples 10 flatwise to the outside faces of the end walls 3; and the end flanges 9 of the hinged covers 7 in the closed position thereof overhang said end walls along the upper margins thereof. Each end wall 3 has a transverse notch 12 in the top thereof midway of its horizontal transverse dimension and of a depth sufficient to receive and support the meeting side marginal flanges 8 of said covers in the closed position thereof.

As shown in the drawings, each end wall 3 has an upper marginal flap denoted in its entirety at 13 and includes a downwardly bent marginal flap or portion 14, which extends along the inner side of said end wall to the level of the upper edge of the handhole 4 therein, and an upwardly rebent portion 15 which lies between and in contacting relationship with flap 14 and an adjacent portion of said end wall 3 for the full depth thereof. The lower edge of the folded upper marginal flap 14 of each end wall 3 is formed into a solid bulbous elongated flat reinforcing rib 16 having a convexly curved surface 16^a with a substantial portion 16^a of the rib 16 extending outwardly beyond the plane of the flap 14, and a flat bottom face 16^b disposed flush with the upper edge of the handhole 4 in said end wall.

The folded portions 14 and 15 of the upper marginal flap 13 of the end wall 3 are rigidly secured together and to the inside face of said wall preferably by means of staples 10, thereby providing a rigid end construction above the top of the handhole 4 in said end wall. As shown in the drawings, the upturned portion 15 of the upper marginal flap 13 of the end wall 3 terminates short of each side edge thereof a distance corresponding to the width of the overlapping end flange 6 of the adjacent side wall 5, thereby permitting the free end of the downturned portion 14 of said flap to be secured directly to said end wall opposite said end flanges by the securing staples 10 for the upper end thereof and thus eliminating an extra or fourth ply which would make the stapling operation more difficult.

As shown in Figs. 1, 11 and 16, each end wall 3 of the container is made from a fiberboard blank provided on its outer face with a creased or scored portion 17, which defines the upper marginal flap 13 of the end wall and along which said flap is folded to form the downturned portion 14 thereof, and on its inner face with a creased or scored portion 18 along which said flap is folded to form the upturned or rebent portion 15 of said flap. The blank has the handhole 4 formed in the main body portion thereof and is also provided with a slot 12^a, which extends crosswise of the score 17 midway of the length thereof, and at its upper edge with a notch 12^b, said slot and notch cooperating to form the notch 12 in the upper edge of the completely folded blank. Each of the scored portions 17 and 18 of the end wall blank comprises a groove 19 in one face of the blank and a wider flat topped rib 20 on the other face thereof opposite said groove, the groove formed by the score 18 being slightly wider than the groove formed by the score 17 and the rib formed by the score 18 being considerably wider than the rib formed by the score 17. As shown in the drawings, the groove formed by the scored portion 17 is formed in the outer face of the flap 13 and the rib associated with said groove is formed on the inner face of said flap; and the groove formed by the scored portion 18 is located in the inner face of the end wall blank while the rib associated with said last mentioned groove is formed on the outer face of said blank. Each of the grooves 19 and 19' has flaring sides 21 of transversely convex curvature and is deepest along the side thereof located nearest to the free edge of the marginal flap 13. Along the deep side of each groove 19 and 19', the flaring side thereof has a relatively steep slope that forms a relatively steep angle with the bottom of the groove, while the flaring side of said groove along the shallow side there-

of has a relatively gradual slope that forms a relatively wide angle with the bottom of the groove. Each of the ribs 20 and 20' has substantially flat outer surfaces which merge into sloping sides, and the groove 19' associated with the rib 20' formed by the upper score 18 has its bottom offset laterally with respect thereto in the direction of the free edge of the flap 13 of said end wall blank so as to provide a lesser thickness of board along the deep side of said groove and an excess thickness of board along the shallow side thereof.

With the outer face of end wall blank 3 disposed uppermost, as shown in Fig. 16, the free marginal portion 15 of the marginal flap 13 is folded downwardly and thence inwardly about creased or scored portion 18 flatwise against the inner face of said flap 14. The effect on the specially shaped rib and groove portions formed by the score 18 is shown in progressive stages in Figs. 12 and 13. The contour of the scored portion 18 in its final position, as shown in Fig. 13, comprises the solid bulbous rib 16 with its flat longitudinal edge 16^b and its convexly curved exposed side face 16^a which in the initially folded position of the flap 13 is disposed on the outer face thereof. The folded two-ply flap 13 is next folded inwardly and downwardly about the scored portion 17 flatwise against the inner face of the main body portion of the blank, as shown progressively in Figs. 14 and 15. The contour of the folded scored portion 17 in its final assembled form is shown in Fig. 15 and showing the said flap 13 in substantial parallelism with the adjacent portion of wall 3 and further wherein the elongated solid marginal end edge reinforcing rib 20 of said scored portion is compressed and disposed between the main body portion of the blank and the upper portion 14 of the flap 13 to just the thickness of the marginal portion 15 thereof, and the groove portion 19 of said scored portion forms an upper edge for the end wall 3 with rounded corners 22 and a flat top portion 23.

The distances between the upper edge of the handhole 4 and the median line of the groove 19 of score 17 and the deep side of the groove 19' of score 18 and from the deep side of the last mentioned groove 19' to the upper edge of marginal flap 13 are so related that upon completion of the folding operation, portions 14 and 15 of the flap 13 are in flatwise contact with each other and portion 15 is in flatwise contact with the inner face of the end panel 3, with the upper edge of portion 15 abutting against the compressed rib 20 of the score 17 and with the flat bottom portion 16^b of the bulbous rib 16 formed by the rib 20' of the folded scored portion 18 in substantially horizontal alignment with the upper edge of handhole 4. These distances in the order described for board of 0.90" to 1.10" caliper, are in the ratio of 1.000:1.043:0.864. The ratio will vary slightly with board of greater or less caliper.

The result of this construction is to provide a strong, solid three-ply construction for end panel 3 from the upper edge of the handhole 4 to the rounded-corner, flat-topped upper edge of said end panel. This is the area which is subjected to the greatest strain in manually lifting, handling and transporting the container. Another important advantage of the construction is that due to the flatwise relationship of portions 14 and 15 of the folded marginal flap 13 and the end panel 3, the box end may be readily and advantageously pre-assembled by the manufacturer

by stapling or gluing the plies in their assembled position.

The assembled end panel utilizes the maximum strength properties of all three plies 14, 15 and 3 to form a rigid reinforcing structure capable of carrying a very high top load between the upper edge of the panel and the handhole and of correspondingly high resistance to endwise deflection due to its solid structure throughout.

None of the advantages of the specially designed scores or creases accurately positioned with respect to each other and to the upper edge of handhole 4 and the free edge of flap 13 are possible of attainment through the use of the conventional scores commonly employed in the industry. As illustrated in Figs. 17, 18 and 19, the conventional scores when folded normally and in reverse will never result in the flatwise relationship of the folded flaps, thus making it impracticable to preassemble the end panel by automatic gluing machinery. More importantly, the board may break on either side of the groove or in an irregular diagonal from side to side of both regular and reverse scores so that the register of the bulbous fold adjacent to the inner side of the upper edge of the handhole may vary over prohibitively wide distances and require manual manipulation to effect even a fair degree of registry with said handhole and approximate horizontal fold of the marginal flap at the upper edge of said end wall. Because of the spaces between plies 14, 15 and end panel 3 resulting from the use of conventional scores, the intermediate ply 15 in the assembled form of the box end adds no strength whatever to the panel since it is free to move over a considerable distance and furthermore does not abut with the rib of scored portion 18.

The hereinbefore described container construction has several important advantages. The upper marginal flap 13 of each end wall panel is folded upon itself and against the inner face of end wall 3 with a very high degree of precision due to the unique shape of both the ribs 20 and 20' and grooves 19 and 19' of the scored portions 17 and 18 respectively of the end wall blank and their location with respect to one another and to the handhole 4 and the free edge of depending ply 14. When the folded blank flap 13 of the end wall 3 is folded into its final position the flat bottom portion 16^b of the bulbous rib 16 at the lower edge of the fold invariably registers with the upper edge of the handhole 4 and the three-ply fold may be quickly and easily secured to the inner face of the end wall panel by staples, glue or other means, so as to cooperate therewith to provide a strong and solid triple wall construction above the handhole. The thick solid rib 16 at the lower edge of the fold serves to add further strength and rigidity to the end wall at the level of the top edge of the handhole where the greatest strength is needed and provides a smooth, wide grip for the fingers when they are inserted in said handhole to manually handle or lift the container. The shape and depth of the grooves 19 and 19' of the scored portions 17 and 18 respectively are so designed as to permit sufficient ply separation to satisfy the draw on the outer plies of the board and accommodate the excess board resulting from the fold without rupture of the fibres themselves during folding; the relatively steep angles along the deep sides of the grooves 19 insure sharp and invariable accuracy of bending along predetermined lines and accurately position the bulbous rib 16 with its flat

bottom surface 16^b flush with the upper edge of the handhole 4. The solid folded construction makes it easy to glue, staple or otherwise secure the folded upper marginal flap 13 of the end wall 3 flatwise to the inner face thereof and to the end flanges 6 to the side walls 5 of the container. As a result of the unique design of scores 17 and 18, folding of the end wall panel flaps requires no manual manipulation whatsoever to effect the proper accurate registry and is admirably adapted to automatic machine operation.

What we claim is:

1. A wall for a container comprising a main body portion having an upper folded marginal flap including a rebent portion folded therefrom, the marginal flap defining an upper marginal edge, the rebent portion engaging the inner side of the marginal flap and an adjacent upper end portion of the wall, the flap, rebent portion and the end portion of the wall being in substantial parallelism, an elongated solid flap reinforcing rib formed by and part of the fold of the flap and the rebent portion, a substantial portion of the flap reinforcing rib extending outwardly beyond the plane of the flap at the fold, an elongated solid marginal edge reinforcing rib interiorly of, formed by, and part of the fold of the flap and the wall, the cross sectional thickness of the end edge reinforcing rib being substantially equal to the cross-sectional thickness of the rebent portion with the free end edge of the rebent portion being in abutting relationship with the end edge reinforcing rib, and means to secure the flap and rebent portion together and to the wall.
2. A container as defined in and by claim 1 wherein the flap and rebent portion are in contacting relationship throughout, and the rebent portion also contacts the adjacent wall portion throughout.
3. A container as defined in and by claim 1 wherein the wall is provided with a handhole having an upper edge, and a lower portion of the flap reinforcing rib is aligned with the upper

edge of the handhole, thereby reinforcing the handhole and providing a smooth gripping surface.

4. A substantially flat paperboard wall blank for a container comprising a one-piece wall portion, flap, and rebendable portion, the flap and rebendable portion extending from an edge of the wall portion and in the same plane therewith, inner and outer spaced-apart foldable score lines defining the flap and rebendable portion, the inner score line presenting an inner groove on one face of the blank and a rib on the other face thereof, the outer score line presenting a rib on the said one face at the juncture of the flap and rebendable portion and a groove on the said other face at the juncture of the flap and the rebendable portion, the width of the inner groove and rib being less than the width of the outer groove and rib, and the bottoms of the grooves being oppositely inclined with respect to the plane of the blank, and with the deepest portions of the bottoms of each groove facing toward the rebendable portion.
5. A wall blank as defined in and by claim 4 wherein the bottom of the groove of said outer score is offset laterally with respect to the rib portion of said score in the direction of the rebendable portion of said blank.
